Des. 663

Samuel A. Sailor, of Philadelphia, Pa.

Assignor to

Abbot & Lawrence, of Philadelphia, aforesaid.

Letters Patent No 663, Dated Aug. 8th 1854.

The schedule referred to in these Letters Patent and making part of the same,

To all whom it may concern:

Be it known, that I, Samuel A. Sailor, of the city and County of Philadelphia, and State of Pennsylvania, have produced a new and original design for Cook stoves called the

"Champion Cook";

and I do hereby declare that the following is a full, clear, and exact description of the

same; reference being had to the annexed drawing forming part of this specification, in which.

Figure 1. is a front elevation of the stove, and

Figure 2. is a side elevation of the same.

Similar characters of reference denote the same part of the stove and design. Symmetrical ornaments have but one half of their details given.

The front doors A are each surrounded by a moulding B, made up as shown by the section x x, thus forming a panel which bears the crooked bands a and b entwined with the foliage c: the bands bearing the projections d and the whole arrangement and configuration of both moulding and ornaments being as set forth in figure 1.

Each side plate C has the three raised panels D, E, F, surrounded by mouldings I I, I, J, as shown by the sections m m, y y, y y. The panel D bears in bas-relief the ornament K made up of the curved band e entwined with the foliage f; the band bearing the projections i, and the whole configuration and arrangement being as set forth in figure 2.

The panels E and F bear in bas-relief the entwined bands g, g', and h, h', the configuration, design, and arrangement being as set forth in figure 2.

Above the panels D are inscriptions in raised capitals and numbers, as follows. "Champion Cook. Patented 1854." arranged as set forth in figure 2.

The top plate is edged with the moulding G, and the base plate is surrounded by the moulding P, the configuration and arrangement being as set forth in the drawing.

What I claim as my production, and desire to secure by Letters Patent, is

The design, configuration, and arrangement of the ornaments in bas-relief and mouldings on the several plates, as herein described, and set forth in the annexed drawing; forming a new and original design, for stove called "Champion Cook."

In testimony whereof, I have hereunto signed my name before two subscribing witnesses.
